ARC LAMP

Elmer C. Richardson, Los Angeles, Calif., assignor
to Mole-Richardson, Inc., Los Angeles, Calif., a
corporation of California

Application September 27, 1933, Serial No. 691,143

2 Claims. (Cl. 176—58)

This invention relates to electric lamps of the character known as arc lamps, and has particular reference to the type of arc lamps employing twin or double arcs for illumination purposes.

5 In connection with certain industries requiring strong lighting, it is common practice to employ arc lamps as a source of illumination. One of such industries is the motion picture industry in which a strong, steady light is essential, and a 10 common form of lamp employed in this industry is one known as "The Twin Arc Lamp", consisting essentially in two sets of carbons arranged in close relation to each other and suitably connected in electrical circuits so as to operate to draw two 15 electric arcs.

The construction of twin arc lamps as now generally used consists primarily of a suitable pedestal or support upon which the lower or stationary carbons of each of the two sets of arcs 20 are rigidly mounted, while the two movable carbons are mounted each upon its own separate yoke, and both yokes are connected to a single controlling magnet or solenoid so that the actuation of the solenoid moves both sets of carbons 25 simultaneously independent of whether or not one of the carbons requires adjustment or movement.

It has been discovered that by separately controlling each of the sets of carbons constituting the arcs, the resultant illumination is greatly increased since each of the arcs may be drawn to its most efficient length independent of the length of the twin or associated arc.

30 It is, therefore, an object of this invention to provide a twin arc lamp in which the sets of carbons employed for producing each of the arcs is individually controlled.

Another object of the invention is to provide 35 a twin arc lamp in which a controlling solenoid is provided for each of the sets of carbons.

Another object of the invention is to provide 40 a twin arc lamp of the character set forth in the preceding paragraph in which the controlling element of each arc comprises a solenoid having a current winding and a voltage winding, the current windings for the two arcs being connected in series relation, while the voltage winding for each of the solenoids is connected in parallel 45 relation to its individual set of carbons.

Other objects and advantages will be apparent 50 from a study of the following specifications, read in connection with the accompanying drawing, wherein

55 Figure 1 is a perspective view of a portion of

an arc lamp structure illustrating the twin arcs and their controlling apparatus constructed in accordance with this invention; and

Figure 2 is a diagrammatic view illustrating 5 the wiring connections for the solenoids and the carbons employed in the practice of this invention.

Referring to the drawing, there is illustrated a suitable supporting plate 1 which may be of any desired character, constituting a portion of 10 the frame or mounting for the arc lamp structure. In illustrating the invention herein, the cover for the controlling apparatus and the reflectors or casings employed for the complete makeup of the arc lamp structure, has been 15 omitted, though it will be understood by those skilled in the art that the mounting plate 1 will constitute a mounting plate for the carbons and their control apparatus, and that a suitable reflector may be employed for the purpose of projecting the light from the arcs upon any desired 20 position, and that any type of housing may be built around the mechanism as may be desired.

The mounting plate 1 is illustrated as being 25 constructed of insulating material, though it will also be understood by those skilled in the art that the mounting plate may be composed of 30 conducting material providing the various pieces of apparatus mounted thereupon are electrically insulated therefrom. The mounting plate 1 is 35 illustrated as being provided with a pair of brackets 2 and 3 secured near the lower end thereof. The bracket 2, having an enlargement 4 upon its outer end, through which a suitable opening 5 may extend vertically for the reception 40 of the lower or stationary carbon 6 for one of the arcs, may be fixed therein by means of a suitable wing bolt or set screw 7, or other clamping means.

The bracket 3 is illustrated as being provided 45 with a suitable opening 8 for the reception thereof of the lower carbon 9 constituting the stationary carbon of the arc. Directly in vertical alignment with the bracket 2 is an upper bracket 10 constituting the support for the upper or movable carbon 11 associated with the stationary carbon 6. The upper carbon is preferably held 50 in position upon the bracket 10 by means of a suitable carbon feed clutch 12 which may be of any well-known construction, such as that commonly employed in arc lamp practice as including a relatively flat plate having an opening therethrough somewhat larger in diameter than the diameter of the carbon which is used so that by securing the rear end 13 of the clutch 12 to 55

an elevating mechanism, such as a lever 14, the lifting of the lever will "cant" the clutch to cause it to grip and lift the carbon 11. The lever 14 is illustrated as being pivotally mounted as at 15 upon a suitable bearing 16 supported upon the bracket 10, the rear end 17 of the lever 14 extending to the rear of the mounting plate 1 to permit the connection thereto of a yoke 18 which is in turn connected to the magnetic core 19 of a suitable control solenoid 20, the yoke 18 being insulated from the lever 14 by any of the various means known to the art.

The solenoid 20 is illustrated herein as comprising two separate coils, 21 and 22, the coil 21 being formed of relatively heavy wire capable of carrying the current employed by the arc between the carbons 6 and 11, while the coil 22 is wound of relatively fine wire and has its magnetic poles opposed to the magnetic poles of the winding 21. Thus by connecting the coil 21 in series relation with the carbons 6 and 11 any current flowing through the carbons will tend to draw the core 19 into the solenoid and thus separate the carbons until the resistance across the arc so formed between the carbons reduces the current flowing in the coil 21 and a state of balance is achieved. The coil 22 is connected in shunt relation with the carbons 6 and 11 so that increase of potential drop across the arc will permit an increased current to flow through the coil 22. With this type of control the algebraic sum of the pole of the coil 21 on its core 19 and the magnetic balance of the coil 22 negativing the magnetic force of the coil 21 will balance the weight of the carbon 11 when the carbons 11 and 6 have been separated by a less distance than if the coil 21 is used alone. Also the effect of the coil 22 is to retard the movement of the carbon 11 and thus cause the carbon 11 to be slowly drawn to the balanced position, thus slowly drawing the arc and maintaining the arc at its most efficient length.

The electric values of the coils 21 and 22 may be selected, as will be understood by those skilled in the art, to feed the carbons to the desired arc length, though I prefer to provide an adjustment for the arc length which may consist of a suitable counterbalance 23 mounted upon an expansion screw 24 secured rigidly to the lever 14 so that by moving the counterbalance 23 toward the pivot 15, or away from the pivot 15, the arc length achieved by balance of the weight of the carbon with the magnetic forces may be varied. The counterbalance 23 may also be adjusted to compensate for changes in line voltage to insure that the intensity of the arc may be maintained constant, though the supply voltage may be materially reduced or increased.

It has been discovered that if the current coil is constructed approximately three times as long as the voltage coil and that if the core 19 is constructed to be of a length slightly less than the length of the current coil, a peculiarly desirable result is achieved in the operation of the arc, namely, that the rapidity with which the arcs may be struck and brought to their normal feeding cycle is materially lessened, and moreover the intensity of the illumination produced by the arcs during the period between the striking of the arc and the time they are operating on their normal feeding cycle is substantially constant, thereby eliminating that initial period of the operation of arc lamps during which the amount of illumination produced varies between relatively great lengths. This is particularly important in

the motion picture industry, as it is essential that the lamps be operated only during the time their illumination is actually required because photographic exposure is proportional to the light intensity and it is highly desirable to maintain a uniform light intensity during the photographing period and because of the intense heat produced by many arc lamps on a motion picture set and yet the instant the illumination is required the full constant degree of illumination of the lamps is immediately necessary.

Similarly the upper or movable carbon 25, constituting the movable carbon associated with the stationary carbon 9 may be mounted upon a bracket 26 through the agency of the suitable clutch 27 identical with the clutch 12, and connected in the same manner through a lever 28, the extending end 29 of which is connected to its own individual yoke 30 to its own individual controlling solenoid 31, which solenoid, like solenoid 20, is composed of a current coil 32 and a voltage coil 33. The current coil 32 of the solenoid 31 is connected in series relation not only with its associated carbons 9 and 25, but also in series relation with the coil 20 and carbon electrodes 6 and 11, while the voltage coil 33 is connected in shunt relation to its associated carbons 9 and 25 to be affected solely by the length of arc drawn between the carbons 9 and 25.

By referring particularly to Figure 2 it will be observed that the twin arc lamp constructed in accordance with this invention may utilize the common practice of connecting the two arcs of the twin arcs in series relation as by supplying current from the positive terminal of a suitable source of electric supply, indicated by the sign plus, through suitable ballast-resistance 34 to one terminal of the coil 21 and thence from the other terminal of the coil 21 through a conductor 35 to the movable carbon 11; thence the circuit may continue through the arc drawn between the carbon 11 and the carbon 6 and thence by way of conductor 36 to one end of the current coil 32 associated with the other set of carbons and from the other terminal of the coil 32 to the movable carbon 25 associated with the carbon 9. The return circuit from the carbon 9 may be carried through a conductor 37, ballast-resistance 38 to the negative side of the source of power indicated by the minus sign. In Figure 2 the connection of the voltage coil 22 is illustrated as extending between the conductor 36 and the conductor 35 while similarly the voltage coil 33 is connected between conductors 37 and 38 to be in shunt relation with the carbons 25 and 9.

By referring particularly to Figure 2, it will be noted that the two solenoids 20 and 31, as shown in Figure 1, are mounted upon the plate 1 in relatively close relation and have their axes parallel to each other.

It has been discovered that by connecting the windings of the two coils 21 and 32 so that the polarity of the lower end of one of the coils is opposite to the polarity of the lower end of the other coil, a substantially closed magnetic circuit is provided between the two coils materially preventing the magnetic field produced by either coil from extending to and affecting either of the arcs drawn between the sets of carbons. Thus by employing the two sets of carbons, each with its individual solenoid, each set of carbons may be individually controlled to draw an arc of the greatest intensity and greatest efficiency. Moreover, the burning away of the

- carbon of one set will cause its particular feeding and controlling mechanism to operate without materially affecting the intensity or length of the arc drawn between the other set of carbons. By 5 employing the voltage coil and current coil opposing each other the burning away of one set of carbons will be accompanied by an increase in the magnetic force of the voltage coil for that carbon, opposing the current coil for that carbon, 10 and will permit the burning away carbon to feed down toward its stationary carbon to maintain the arc length approximately constant until its clutch 12 contacts with its bracket, at which time the clutch will release the carbon, feeding 15 the movable carbon toward the stationary carbon and/or adjusting the arc again to its proper length.

Such arrangement avoids the primary disadvantage of previously constructed twin arc lamps 20 in which a single feeding and controlling coil was employed for handling both movable carbons, since the burning away of one carbon would cause movement of both carbons even though the other set of carbons had not burned at the 25 same rate. Such operation prevented the arcs from operating at their maximum efficiency.

While the preferred embodiment of the invention is illustrated herein, it is not desired to be limited to any of the details shown or described herein, except as defined in the appended 30 claims.

I claim:

1. In a twin-arc lamp mechanism, a vertical

supporting plate, a pair of juxtaposed brackets extending from the lower portion of said plate on one side thereof for supporting a pair of lower carbons, a pair of means also mounted on said plate adjacent the upper end thereof for supporting a pair of upper carbons above said lower carbons, each of said means comprising a lever fulcrumed in front of said plate, means on the forward end of said lever for supporting the associated upper carbon, the rear end of each 10 lever extending to the rear of said plate and having a downwardly extending magnetic core attached thereto, a solenoid surrounding each core and comprising a current coil connected in series with the associated arc and a potential 15 coil connected in shunt to the associated arc and poled to oppose the current coil of that solenoid, and a movable counterweight on each lever means for balancing that lever and its associated carbon and magnetic core to compensate for variations in the potential of the current from which the arc is energized.

2. An arc mechanism as described in claim 1 in which said solenoids are positioned in substantially juxtaposed relation to their associated 25 arcs and in juxtaposed relation to each other and in which the two solenoids are so poled relative to each other that their magnetic fields are in large measure restricted to a closed path through the two solenoids, thereby reducing the 30 stray field in the vicinity of the said arcs.
